ENVELOPE SEAL

Everett W. Sharkey, Woodhaven, N. Y.

Application October 2, 1936, Serial No. 103,651

6 Claims. (Cl. 292—307)

This invention relates generally to an envelope or container seal, but more particularly to a substitute for the present wax impressed seal; the substitute construction serving as a safety clasp for envelopes adapted to contain documents, letters, blue-prints, models and the like, to be held in escrow or conveyed through the mails intact.

The main object of the invention resides in the provision of an envelope seal or safety clasp which operates conjointly with the gummed sealing flap on the principle of a latch so that the contents cannot be ascertained without destroying both the envelope and the safety clasp.

Another object of the invention resides in the provision of a safety clasp which is easily applied to an envelope or other container having a sealing flap and wherein a minimum amount of initial pressure of the hand operates the latching means into permanent locking position, there being no projections which might tend to injure the contents of the envelope and there being no projecting tongues which require the necessity of being flattened out by the above mentioned pressure.

A further object of the invention resides in the provision of a clasp on the outer flap of which a monogram or coat-of-arms may be stamped, the clasp itself being capable of being stamped from a resilient metal blank.

Another object of the invention resides in the provision of a clasp which is of simple construction, which is economical to manufacture and which is aesthetic in appearance.

These objects and other incidental ends and advantages of the invention will hereinafter appear in the progress of the disclosure and as pointed out in the appended claims.

Accompanying this specification is a drawing showing a preferred form of the invention and wherein corresponding reference characters designate corresponding parts throughout the several views.

In accordance with the drawing:

Figure 1 is a plan view of the rear surface of an envelope with the safety clasp affixed thereto in operative position.

Figure 2 is a sectional view of Figure 1 along the plane 2—2 thereof.

Figure 3 is a sectional view of Figure 4 along the plane 3—3 thereof.

Figure 4 is a plan view of the safety clasp per se, a part thereof being broken away.

Figure 5 is an end elevation of the safety clasp shown in Figure 4.

In accordance with the invention shown in the accompanying drawing, a form thereof is now to be described.

A container having a sealing flap such as envelope 9 is used in conjunction with the new and

improved safety clasp. Envelope 9, as shown, is provided with a rear body surface 10 and the ordinary gummed sealing flap 11. Numeral 12 indicates the upper edge of the rear body surface 10 of the envelope.

The safety clasp is preferably formed from an elongated strip of resilient metal which is adapted to be folded to provide a front flap 13, a rear flap 14 and an intermediate flap 15, the said folding resulting in a clasp having a substantially Z-formation.

The intermediate flap 15 is preferably narrow and uniform in width while the front and rear flaps 13 and 14 respectively preferably taper to a greater width towards the central vertical axis and are correspondingly reduced toward the opposite end, as best shown in Figures 1, 4 and 5. Thus the front flap 13 is wide enough to bear the seal, monogram or coat-of-arms impressed thereon of the user. If desirable, the width of flaps 13, 14 and 15 may all be uniform. It is to be observed, however, that the wider 13 and 14 are, the easier it is for the user to bear initial pressure on the front flap for purposes of latching the clasp in permanently locked position, as will hereinafter appear.

Depending from the front flap 13 are a pair of spaced latching fingers 16 and 17, the lower terminals of which are provided with upwardly offset portions 18 and 19. Latching finger 16 penetrates the intermediate flap 15 at one end thereof, as indicated by numeral 20, in view of the proximity between the said intermediate flap 15 and the front flap 13; while latching finger 17 terminates slightly above the intermediate flap 15 near the end thereof by virtue of the increased distance between the said two flaps.

Rear flap 14 is provided with a latching plate member 21 for the offset portion 18 of latching finger 16. The said latching plate member 21 is formed by folding the open end portion of rear plate 14 upwardly and inwardly, as best shown in Figure 3. The latching plate member 21 is provided with an aperture 22 which is eccentrically mounted with respect to latching finger 16. The degree of eccentricity between latching finger 16 and aperture 22 determines the deflection of latching finger 16 when the lower surface of offset portion 18 is wedged outwardly on the upper surface of latching plate member 21 in order to penetrate aperture 22. Following the penetration of offset portion 18 of finger 16 through aperture 22, a release of pressure on latching finger 20 effectuates a permanent locking between the offset portion 18 and the lower surface of the latching plate member 21. This is, of course, due to the return of latching finger 20 after it has passed through the relatively eccentrically positioned aperture 22 and pressure has been released.

Intermediate flap 15, near its folded end, serves as a latching plate member, as indicated by numeral 23, similar in function to latching plate member 21. An aperture 24 is therein provided corresponding to aperture 22, the said aperture 24 also being eccentrically mounted relative to latching finger 17. In order to avoid the offset portions 18 and 19 from penetrating the envelope when in any possible position, rear flap 14 is provided with two spaced recesses 25 and 26, the said recesses being in vertical alignment with apertures 22 and 24, respectively. The purpose of recesses 25 and 26 is to house the offset portions 18 and 19 when pressure is applied to front flap 13. Of course, upon the release of such pressure, the offset portions 18 and 19, together with fingers 16 and 17, rebound to be engaged by the undersurface of latching plate member 21 and latching plate member 23, as best shown in Figure 2. The safety clasp above described is easily applied and operated on any container having a sealing flap. After the contents are inserted in the envelope or container, the sealing flap, if gummed, is moistened. Thereupon, the safety clasp is applied to the free edge 12 intermediate the width thereof, so that the rear body portion 10 of the envelope is situated between the intermediate flap 15 and rear flap 14. When this is done, the folding flap 11 of the envelope is passed between the front flap 13 and the intermediate flap 15 through the opening therebetween, as illustrated on Figure 3. Thereupon, initial pressure is applied to the upper surface of front flap 13 until the clicks of the latching fingers 16 and 17 are heard as they penetrate apertures 22 and 24, the pressure then being released. Upon the release of pressure, offset portions 18 and 19 permanently lock against the undersurface of latching plate members 21 and 23, respectively. During the application of pressure, the fingers 16 and 17 penetrate the body surface 10 and the folding flap 11 of the envelope, it being impossible for the said latching fingers to penetrate the front wall of envelope 9 by virtue of the recess 25 and 26, as indicated in Figure 2. The permanent locking arrangement of fingers 16 and 17 makes it impossible to open the safety clasp without destroying the same. Moreover, only that amount of pressure as applied to front flap 13, is required to bring about the penetration of the latching fingers 16 and 17 through apertures 22 and 24, respectively. The element of flattening out projecting tongues is absent in the present construction, thereby relieving the user of applying excess pressure on front flap 13. The operation of the present clasp really operates on the mortise and tenon joint principle wherein the mortise is eccentrically disposed in relation to the tenon. I wish it understood that minor changes and variations in the material used, in the integration and location of the several parts, may be resorted to without departing from the spirit of the invention and without departing from the scope of the claims.

I claim:

1. A safety clasp for article holders having a sealing flap, comprising an outer and inner flap, an intermediate flap joining the opposite ends of said outer and inner flaps, resilient latching fingers depending from the outer flap, two apertured latching plate members situated inwardly of the

ends of the inner flap, the first being integral with the inner flap and the second integral with the intermediate flap, the inner flap having a pair of spaced depressions in vertical alignment with the apertures of the plate members, the said depressions recessing the terminals of the fingers upon initial pressure to the outer flap whereupon the fingers rebound to latch with the undersurface of the said plate members. 5

2. A safety clasp for article holders having a sealing flap, comprising an outer and inner flap, an intermediate flap joining the opposite ends of said outer and inner flaps, resilient and spaced latching fingers depending from the outer flap, one of the said fingers penetrating the end portion of the intermediate flap, two apertured latching plate members situated inwardly of the ends of the inner flap and thereabove, the first being integral with the inner flap and the second integral with the intermediate flap, the inner 15 flap having a pair of spaced depressions in vertical alignment with the apertures of the plate members, the said depressions recessing the terminals of the fingers upon initial pressure to the outer flap whereupon the fingers upon release 25 of pressure rebound to latch with the undersurface of the said plate members.

3. A safety clasp for article holders having a sealing flap comprising an elongated member folded to provide an outer, inner and intermediate flap resilient latching fingers depending from the outer flap, one of the said fingers penetrating the end portion of the intermediate flap, two apertured latching plate members situated inwardly of the ends of the inner flap the first plate 35 member being an upwardly and inwardly turned end portion of the inner flap and the second plate member being one end portion of the intermediate flap, the inner flap having a pair of spaced depressions in vertical alignment with the 40 apertures of the plate members, the said depressions recessing the terminals of the fingers upon initial pressure to the outer flap whereupon the fingers upon release of pressure rebound to latch with the undersurface of the said plate members. 45

4. In a safety clasp for article holders having a sealing flap in combination with an elongated member folded to provide an outer, inner and intermediate flap, and with resilient latching fingers depending from the outer flap, two apertured latching plate members for the said latching fingers continuous with and integral with the inner flap. 50

5. In a safety clasp for article holders having a sealing flap, in combination with an elongated member folded to provide an outer, inner and intermediate flap, and with resilient latching fingers depending from the outer flap, one of the said fingers penetrating the end portion of the intermediate flap, two apertured latching plate 60 portions for the said latching fingers forming part of the intermediate and inner flaps. 65

6. In a safety clasp for article holders having a sealing flap, in combination with an elongated member folded to provide an outer, inner and intermediate flap, and with resilient latching fingers depending from the outer flap, two apertured latching plate members for the said latching fingers respectively formed with the inner and intermediate flap. 70
